M. T. Hitchcock Inventor

United States Patent Office.

M. T. HITCHCOCK, OF SPRINGFIELD, MASSACHUSETTS.

Design No. 3,670, dated September 28, 1869.

DESIGN FOR A RAILWAY-CAR VENTILATOR-CASE OR SHELL.

The Schedule referred to in these Letters Patent and making part of the same.

To all whom it may concern:

Be it known that I, M. T. HITCHCOCK, of Springfield, in the county of Hampden, and State of Massachusetts, have invented a new Design for a Railway-Car Ventilator-Case or Shell; and I do hereby declare the following, when taken in connection with the accompanying drawings, and the letters of reference marked thereon, to be a full, clear, and exact description of the said design, and which said drawings constitute part of this specification, and represent, in—

Figure 1, a perspective view of a car-ventilator shell, made according to my design.

Figure 2 represents a side elevation of the same; and

Figure 3 is an end view of the same.

My invention relates to the form or shape of the shell or case of a ventilator, designed to be attached to the side of the "deck" of what is known as "monitor" railway-cars.

That others skilled in the art may be able to make and use my invention, I will proceed to describe its construction and its application to use.

In the drawings—

B B represent the upper and lower sides of the case; and

D represents the ends of the shell or case, and at the ends E, and also at the sides B, are the flanges b b.

This part of the case having the flanges b thereon is quadrangular in form, to adapt it to the window or ventilating-aperture in the car, in connection with which it is to be used.

The two sides B B are joined or united at the side of the shell or case, opposite that upon which are made the flanges b b, by the curved part C, and an opening, E, extends inward from each end of the shell or case.

Having thus described my invention,

What I claim as new, and desire to secure by Letters Patent, is—

The design for a railway-car ventilator-shell or case, substantially herein shown and described.

M. T. HITCHCOCK.
